(57) **CLAIM**

The ornamental design for a portion of golf club head sole plate, as shown and described.

DESCRIPTION

FIG. 1 is a plan view of a portion of golf club head sole plate;
FIG. 2 is a rear view thereof;
FIG. 3 is a perspective view thereof; and,
FIG. 4 is a heel perspective thereof.
The broken line showing of the remainder of the club head
is for illustrative purposes only and forms no part of the
claimed design.
